UNITED STATES PATENT OFFICE.

JOHN MONTGOMERY, OF TORONTO, CANADA.

CYLINDER KNOB-LOCK.

No. 823,348.

Specification of Letters Patent.

Patented June 12, 1906.

Application filed February 17, 1905. Serial No. 246,015.

To all whom it may concern:

Be it known that I, JOHN MONTGOMERY, a subject of the King of Great Britain, residing at the city of Toronto, county of York, Province of Ontario, Canada, have invented a certain new and useful Improvement in Cylinder Knob-Locks; and I declare the following to be a full, clear, and exact description of the invention, such as will enable others skilled in the art to which it pertains to make and use the same, reference being had to the accompanying drawings, which form a part of this specification.

This invention relates to cylinder knob-locks.

It has for its object an improved combined latch and knob-lock adapted to be used with doors of ordinary construction and to be attached to the door as a mortise-lock without cutting the deep and wide mortise that is usually required, but by simply mortising to receive the face-plate and boring for the insertion of the latch-shank, with a bore through the door for the passage of the knob-spindle.

In the drawings, Figure 1 is a plan view showing the latch and its connection with the knob-spindle. Fig. 2 is a vertical section longitudinal of the latch-shank and across the knob-spindle. Fig. 3 is a section lengthwise of the knob-spindle. Fig. 4 shows one end of the knob-spindle with the unlocking key inserted. Fig. 5 is an elevation, partly in section, of the assembled lock. Fig. 6 shows the means of attaching the knob to the spindle.

The face-plate 1 is a rectangular piece of metal adapted to be inserted in a shallow mortise in the edge of the door. To the back of the face-plate 1 is secured a guide-bracket 2, through which passes the stem 3 of the latch-bolt. Between the back of the bracket 2 and a shoulder at the back of the projectile part of the latch-bolt 3 is a spring 4, which tends to hold the latch projected. At the back of the latch-bolt is a yoke 5, that engages around the spindle 6. The yoke 5 is provided with slots 5^a on both its upper and lower sides and with an entrance-notch 5^b to each slot. At the back of the yoke where it bends around the spindle is notch 7, that extends from the side inward deep enough to receive the end of a pin 8, which serves as the locking means between the spindle and the latch. The spindle 6 is provided with a slot 10 near its middle point. Within the sleeve is an arbor 11, threaded at its middle part and provided

at its ends with plugs 18, which fill the bore of the sleeve, (except for a keyhole hereinafter mentioned.) On the threaded middle part of the arbor 11 is a running-nut 12, provided with a pin 8, that projects through the slot 10 and terminates with a head 8^a. A knob is secured to each end of the spindle 6. Two pins 5^c 5^d project radially from the spindle and engage in the slots 5^a of the yoke. The pins 5^c 5^d are located to oscillate in a path which if continued to the full revolution would coincide with the path of one end of the slot 10. The slot 10 is long enough to allow the pin 8 to be run along the slot to a position to oscillate without engaging the yoke, or it may be run along the slot 10 until it will engage in the notch 7.

At either end of the spindle is a rotative tumbler-carrier 17, provided with a slot 14 for the reception of a locking-tumbler 15, and in the spindle 6 in a position to register with the slot 14 is a groove 16. The locking-tumbler 15 is pivoted to hang in the slot 14 and to normally hang with one end projecting into the groove 16, in which position the tumbler-carrier and the sleeve are locked and are not capable of independent rotation. At the outer end each tumbler-carrier 17 has a peripheral groove 19, in which engages a pin 20, that is inserted through the spindle 6. Each tumbler-carrier 17 is provided with a keyway or keyhole 21, through which the key 22 may be inserted under and past the tumbler 15, and if the proper key be inserted the tumbler 15 will be swung until it is disengaged from its position within the groove 16, at which time the key projects into the keyway 22^a in the plug 18, which is secured to the end of the arbor 11 in position to rotate with it, and the turning of the key turns the arbor without turning the spindle 6. The rotation of the arbor produces a longitudinal movement of the pin 8 along the axis of the sleeve, because of the threading on the arbor 11, which engages through the swiveled nut 12. If the pin 8 be drawn into the notch 7, the spindle can no longer rotate.

The tumbler 15 may be compared to a segmental rack having an irregular outline or one that is suspended eccentric to its center of curvature with ratchet-teeth or key-teeth thereon that differ the one from another, and the key may be compared to a rack which actuates the segment, but one in which the special key must fit the special tumbler or the tumbler will not reach its unlocking posi-

tion at a time when the key is in a position to turn the arbor and at the same time escape the pin 20, for which purpose the key must be notched. In inserting this lock in place 5 it is only necessary to bore a single round hole from the edge of the door to meet a single round hole that is bored through the door for the knob-spindle. Each rose 24 is preferably provided with a neck 25, that centers 10 the knob-spindle.

The headed pin 8 by engagement with its large head over that portion of the yoke 5 which engages around the sleeve 6 and is immediately adjacent to the inner end of the 15 notch 7 prevents the latch from being pushed inward and the door unlocked by the insertion of any thin or sharp object in front of the latch. That portion of the spindle which in the assembled structure projects 20 from the door and is intended to engage within the hollow of the knob is provided with a number of screw-holes 30, arranged along a spiral line around or partly around the spindle, and the knob is provided with a shank 31, 25 with a single screw-hole for the screw 32. The screw engages in that one of the holes which brings the shank of the knob as close to the surface of the door as the neck 25 of the rose 24 will permit.

30 The removal of the knob does not give access to the operative parts of the locking mechanism, nor can the spindle be pushed through the door or out of place without first gaining access to the projectile part of 35 the latch, which must be pushed back at a time when the pin 8 is not in position for the head 8^a to engage over the yoke. There is a mutual interlocking of the several parts in that the engagement between pin 8 and yoke 40 prevents the spindle from turning. Engagement between head 8^a and the yoke prevents the latch from being pushed back, and engagement of the pins 5^c 5^d in the slots of the yoke prevents the spindle from moving to 45 either side.

What I claim is—

1. In a cylinder knob-lock, in combination, a rotary spindle provided with projecting pins, a latch provided with a yoke adapted to 50 engage around said spindle, said yoke being provided with slots wherein said pins engage, and a member movable with respect to said spindle provided with a projecting portion, normally out of engagement with said yoke 55 adapted to be moved to a position of locking engagement therewith, substantially as described.

2. In a cylinder knob-lock, in combination with a rotary spindle slotted near its middle 60 point, a rotary arbor within said spindle having a screw-threaded center portion, a running-nut on said screw-threaded portion pro-

vided with a pin extending through the slot, rotative tumbler-carriers within said spindle between each end of the arbor and the ends 65 of the spindle, means located near each end of the spindle for holding said tumbler-carriers from escape, a tumbler for each carrier adapted to interlock the carrier and the spindle, and to be unlocked only by its appropriate key, a yoke engaging about the spindle provided with a slotted portion adapted to be engaged by said pin, and a latch-bolt carried on the other end of the yoke from the spindle-engaging portion, substantially as 75 described.

3. In a cylinder knob-lock, the combination of a latch-bolt, a slotted yoke carrying the same, a spindle passing therethrough, that portion of the spindle engaging said 80 yoke having a plurality of projections adapted to engage in the slotted portions thereof, a pin member also projecting from said engaging portion of the spindle, a running-nut within the spindle whereon said pin is mounted and means adapted to be manually actuated for throwing said pin to interlocking engagement with said yoke, substantially as 85 described.

4. In a knob-lock, in combination a spindle provided with projecting pins, a latch-bolt, a yoke therefor provided with bayonet-slots for engagement with said pins, whereby the yoke and the spindle can only be disengaged when the projectile part of the latch is 95 retracted, substantially as described.

5. In a cylinder knob-lock, in combination, a latch-bolt, a yoke carrying the same, a spindle engaging through said yoke and adapted to be interlocked therewith, an arbor within 100 said spindle, and means carried by said arbor and extending outside of said spindle adapted to be moved with said arbor with respect to said spindle into a position of binding engagement with said yoke.

6. In a cylinder knob-lock, in combination a rotary spindle provided with projecting pins, a latch-bolt provided with a yoke member engaging thereabout, said yoke being provided with slots wherein said pins engage, an arbor within said spindle and rotatable with respect thereto, said arbor being screw-threaded along its middle portion, a running nut on said screw-threaded portion, said nut carrying a headed pin extending outside said 110 spindle, and means for actuating said arbor to cause said headed pin to bindingly engage said yoke, substantially as described.

In testimony whereof I sign this specification in the presence of two witnesses.

JOHN MONTGOMERY.
